UNITED STATES PATENT OFFICE.

HERBERT R. MARSH, OF PHILADELPHIA, PENNSYLVANIA, ASSIGNOR OF ONE-HALF TO DANIEL F. RYAN, OF KIRKLYN, PENNSYLVANIA, MUTUAL TRUST COMPANY OF PHILADELPHIA, EXECUTOR OF SAID DANIEL F. RYAN, DECEASED.

METHOD OF AND APPARATUS FOR BURNING LIQUID FUEL.

Application filed August 20, 1928. Serial No. 130,374.

The object of this invention is to devise a novel method of and apparatus for burning liquid fuel in which a better commingling action of the oil and air is obtained and 5 wherein provision is made for introducing into the burning gases, additional air in order to obtain complete combustion.

A further object of my invention is to devise a novel method of and apparatus for 10 burning liquid fuel wherein means are provided for preventing dead zones in the combustion chamber.

With the above and other objects in view as will hereinafter more clearly appear, my invention comprehends a novel method of and 15 apparatus for burning liquid fuel.

It further comprehends a novel construction of an oil burner having a novel construction and arrangement of a combustion chamber 20 into which the fuel and air is introduced in a novel manner, and in which a novel circulation of the burning gases is effected.

It further comprehends a novel construction and arrangement of a baffle for causing 25 the additional air introduced into the combustion chamber to be highly heated and to have a definite direction of flow in the combustion chamber.

It further comprehends a construction and 30 arrangement for preventing the formation of dead zones in the combustion chamber.

Other novel features of construction and arrangement will hereinafter more clearly appear in the detailed description and the 35 appended claims.

For the purpose of illustrating the invention, I have shown in the accompanying drawing, a typical embodiment of it, which, in practice will give satisfactory and reliable 40 results. It is, however, to be understood that this embodiment is typical only and that the various instrumentalities of which my invention consists can be variously arranged and organized, and the invention is not, 45 therefore, limited to the precise arrangement and organization of these instrumentalities as herein set forth.

Figure 1 is a top plan view of a liquid fuel burner embodying my invention, and by the 50 use of which my novel method can be carried out.

Figure 2 is a top plan view similar to Figure 1 but having certain of the parts removed for the sake of clearness of illustration.

Figure 3 is a section on line 3—3 of Figure 1.

Figure 4 is a perspective view showing more clearly the combustion pot and certain of its adjuncts.

Similar numerals of reference indicate 60 corresponding parts.

Referring to the drawings.

1 designates the casing or fire pot of an oil burner embodying my invention.

The casing is provided with base flanges 2, 65 which are adapted to receive the customary fastening device to secure the casing to a suitable support.

The casing is provided with an air inlet 3, 70 see more particularly Figure 3, which forms a commingling chamber for the fuel and air and which is in communication with an air duct 4, which leads from a desired source of air under pressure, such as for example, a blower.

5 designates a fuel duct or pipe which leads from a desired source of supply of liquid fuel supply, and this duct or pipe extends into the commingling chamber, as best seen in Figure 3, so that the discharge from the fuel 80 duct 5 will be received on a hot plate or flash pan 6 having its top surface preferably of irregular contour or pocketed, as indicated at 7. The discharge end of the fuel pipe is preferably bent downwardly and cut away at its 85 top.

The pockets as shown are formed by intersecting raised ribs, and the plate is preferably inclined towards one end so that surplus oil can drain off.

Opposite sides of the hot plate 6 are provided with the upwardly extending flanges 8, and the hot plate is secured in position above the bottom of the commingling chamber 3 by means of a desired number of fastening devices 9. The flash pan 6 and its flanges 8 extend forwardly into the combustion chamber 10.

The wall of the combustion chamber 10 in proximity to the inner end of the hot plate 6 is curved inwardly as at 11 and extends forwardly substantially straight across the transverse diameter of the combustion chamber in spaced relationship with the curved inner wall of a baffle 12 rising from the bottom of the casing 1 and preferably integral with it.

This baffle 12 extends preferably slightly

above the top of the casing, as indicated, at 13, see Figure 3, and between the outer wall of this baffle 12 and the inner periphery of the casing 1 is formed an air passage 14 having its inlet end converging as indicated at 15 and in communication with the commingling chamber 3.

The air passage 14 extends for a distance of about two hundred and seventy degrees 10 around the combustion chamber 10 so that the air contained in this passage will be highly heated.

At the discharge end of the passage 14, as indicated at 16, it merges into a reversely directed passage 17, the bottom wall of which is upwardly inclined towards its discharge end as at 18, and this discharge outlet 17 opens by a port 19 located about the bottom of the combustion chamber 10.

The passage 14 is provided with a drain port 20 which communicates with a chamber 21 formed in the bottom of the casing 1, and from this chamber 21 leads a conduit 22 which returns the surplus oil to a desired point of utilization.

It has been found in practice that in some cases, a dead zone occurs in the combustion chamber, or in other words a zone in which complete combustion does not take place, and, to overcome this, I provide a baffle 23 in the form of a cone.

It has been found by careful experimenting, that the best place for this cone, in the form of the invention illustrated, is near the center of the combustion chamber in the right hand inner quadrant, viewed from the inlet to the combustion chamber, between the major longitudinal and transverse diameters of the casing 1.

The casing is provided with a cover 24 which covers the commingling chamber 3 and the combustion chamber 10, and above the chamber 10 this cover converges upwardly towards a discharge opening 25.

The cover 24 carries posts 26 on which are mounted a baffle 27 in the form of a disc, and, while this baffle may be made of any suitable material, I have found that if it is made of carborundum very advantageous results can be obtained.

In order to initially heat the hot plate, I provide a pilot burner 28 to which leads a conduit 29 for the liquid fuel so that the hot plate is initially heated to a desired temperature.

It will be seen that the baffle 12 is eccentric at its outer end and its inner end is in such position that it divides the chamber 3, so that a portion of the air is diverted into the passage 14, passes around the greater portion of the wall of the combustion chamber, and during such travel becomes highly heated.

This auxiliary supply of air and fuel is discharged into the combustion chamber through the discharge port 19 so that it enters

the combustion chamber as illustrated in a reversely inclined direction and in the same direction as the main body of commingled air and fuel, so that a very intimate mixture of the air and oil is obtained and the additional air necessary to obtain complete combustion is introduced into the combustion chamber.

The baffle 23 causes the burning fuel to circulate in the combustion chamber in a direction which is eccentric for a part of its travel and concentric for another part of its travel, and the flame issuing from the burner around the baffle formed by the carborundum disc is in the form of a circular flame.

It will now be apparent to those skilled in this art that my novel method is carried out in practice as follows:

The liquid fuel is fed through the fuel pipe 5 in any desired manner, for example by gravity or by a forced feed. The oil drops on the flash pan 6 which is initially heated by the pilot burner 28 so that the oil is vaporized. After the burner has been running, the pilot burner can be turned off and the flash pan is retained heated by heat derived from the oil burner fire pot. The air under a desired pressure sweeps over the flash pan and commingles with the vaporized fuel and enters the combustion chamber. The wall 11 deflects the commingled gases so that they travel in a path which is first eccentric and then concentric of the combustion chamber.

At a desired distance above the bottom of the combustion chamber, I introduce in the direction of travel of the burning gases highly heated additional air so that the burning gases pass through and are commingled with a strata of highly heated air.

I thus provide sufficient oxygen at the proper temperature to enable a complete combustion of the combustible content of the fuel. I have not deemed it necessary to illustrate and describe the automatic control of the fuel and of the air so that the requisite relative proportions of air and fuel are automatically maintained at all times. The cone shaped baffle 23 not only prevents the dead zone; but tends to cause an upward travel of the gases circulating around it. The additional air also tends to increase the velocity of the travelling gases within the combustion chamber.

In oil burners of this character, the fire pot becomes intensely hot and a considerable amount of heat is lost by radiation.

Special attention is directed to the novel construction of the fire pot, it being seen that I employ an eccentrically disposed baffle forming a wall of the combustion chamber and contributing to form an air passage or chamber within the wall of the cylinder or casing, and this air passage extends around the combustion chamber, preferably for the greater portion of its circumference, so that this air passage has a dual function.

It not only serves to highly heat the air employed for the secondary combustion in the combustion chamber, but it also serves to insulate the wall of the combustion chamber.

It will be seen from Figure 3 that I also preferably provide a drain port 30 so that any oil which is not taken up and commingled with the air will be returned to a point of utilization through the chamber 21 and the conduit 22.

As illustrated in Figure 3 the flash pan at the inlet end of the commingling chamber 3 is higher than at its inner end or in other words it is inclined so that any surplus oil will be drained off.

It will now be apparent that I have devised a new and useful method of and apparatus for burning liquid fuel which embodies the features of advantage enumerated as desirable in the statement of the invention and the above description, and that while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. The method of burning liquid fuel, which consists in vaporizing the fuel, commingling the fuel with air, causing the commingled gases to travel in a path which is first eccentric and then concentric relatively to a combustion chamber, and introducing into the combustion chamber above the commingled gases in proximity to the fuel and air inlet and in the direction of flow of gases in the combustion chamber a stratum of highly heated air and fuel through which the commingled gases pass to their discharge outlet.

2. The method of burning liquid fuel, which consists in vaporizing the fuel and commingling it with air, causing the commingled gases to travel in a combustion chamber in a path which is eccentric and then concentric relatively to a combustion chamber, diverting a portion of the air and fuel and highly heating it, and then introducing it into the combustion chamber in proximity to the fuel and air inlet to cause it to travel in a path which is eccentric and then concentric relatively to the combustion chamber.

3. The method of burning liquid fuel, which consists in vaporizing the fuel and commingling it with air, causing the commingled gases to travel in a combustion chamber in a path which is eccentric relatively to a combustion chamber, diverting a portion of the commingled gases and causing

them to travel in a reverse direction to that of the gases in the combustion chamber around said combustion chamber to receive heat therefrom, introducing the highly heated gases into the inlet portion of the combustion chamber above the bottom thereof and causing them to travel in the combustion chamber in the same direction as that of the commingled gases to cause an intimate commingling therewith.

4. In an oil burner, a casing having a combustion chamber provided with a fuel inlet in its side wall and an air inlet, with the wall of said chamber in proximity to said inlets flaring outwardly, and means to divide the incoming air and to cause a portion of it to pass circumferentially around the greater portion of the side wall of said chamber and enter said chamber in proximity to the fuel and air inlet in the same direction as the flow of the commingled fuel and air.

5. In an oil burner, a casing having interconnecting commingling and combustion chambers, with an air inlet and a fuel inlet to said commingling chamber, a hot plate in the commingling chamber and extending into the combustion chamber, and an eccentric baffle in said casing forming a wall of said combustion chamber and an air passage communicating with said air inlet and reversely directed at its discharge end which latter is in proximity to the inlet to said combustion chamber.

6. In an oil burner, a casing having interconnecting commingling and combustion chambers, with an air inlet and a fuel inlet to said commingling chamber, a hot plate in the commingling chamber and extending into the combustion chamber, and an eccentric baffle in said casing forming a wall of said combustion chamber, and an air passage communicating with said air inlet and reversely directed at its discharge end which latter is in proximity to the inlet to said combustion chamber, and an oil drain leading from said air passage.

7. In an oil burner, a casing having a commingling chamber and a combustion chamber with a fuel inlet and an air inlet to said commingling chamber, a baffle forming a wall of said combustion chamber, and contributing to form a passage communicating with said commingling chamber, extending around said combustion chamber and communicating with it near its inner end, and a cone shaped baffle in said combustion chamber to define the flow of gases therein.

8. In an oil burner, a casing having a commingling chamber and a combustion chamber with a fuel inlet and an air inlet to said commingling chamber, a baffle forming a wall of said combustion chamber, and contributing to form a passage communicating with said commingling chamber, extending around said combustion chamber and com-

municating with it near its inner end, a cone shaped baffle in said combustion chamber to define the flow of gases therein, a cover for said chambers having a discharge outlet, and 5 a baffle above said outlet.

9. In an oil burner, a casing having inter-communicating commingling and combustion chambers, with a fuel inlet and an air inlet for said commingling chamber, an eccentrically disposed baffle forming a wall of said combustion chamber and forming a passage surrounding the greater portion of said combustion chamber and communicating with the inlet end of said commingling chamber, 10 and reversely directed at its discharge end and opening into the inlet portion of said combustion chamber, the wall of said combustion chamber at its inlet portion being curved inwardly to direct the gases towards 15 the central portion of said combustion chamber, a cone shaped baffle rising from the bottom of said combustion chamber in proximity to its central portion, and a cover for said casing having a discharge outlet.

10. An oil burner casing having a fuel and an air inlet, and having an eccentrically disposed baffle forming a wall of its combustion chamber and contributing to form the wall of an air passage which surrounds the 20 greater portion of the combustion chamber and discharges into it in proximity to said fuel and air inlet in the direction of flow of gases in said combustion chamber.

11. In a fuel oil burner, the combination 25 with a combustion chamber and a vaporized oil conduit communicating therewith, of means for introducing vaporized oil under

pressure into the combustion chamber through the conduit, means for dividing the stream of vaporized oil admitted into the 40 combustion chamber into two substantially concentric streams, and imparting a swirling motion to each stream.

12. In a fuel oil burner, the combination with a substantially cylindrical combustion chamber having a flat bottom and an open top, of means for introducing vaporized oil into the combustion chamber under pressure, an inner partition wall of substantially circular form extending around the interior of 50 the combustion chamber and spaced apart from the chamber wall to constitute a substantially circular passage having an entrance into the combustion chamber at one end thereof, a vaporized fuel supply element 55 extending in a radial direction from the combustion chamber, the vaporized oil being introduced thereinto through such element, means whereby the vaporized oil is divided into two streams, one of which enters the combustion chamber, the other of which enters the passage, a vertical wall partially extending across the entrance from the oil supply element to the combustion chamber in order to direct the flow of vaporized oil entering 60 the combustion chamber against the circular wall thereof, and a substantially longitudinally directed vane positioned upon one side of the entrance from the passage to the combustion chamber as a means for directing the 65 flow of vapor from the passage into and with the swirl of vapor in the combustion chamber.

HERBERT R. MARSH.
